UNITED STATES PATENT OFFICE.

ELMER A. SPERRY, OF BROOKLYN, NEW YORK.

METHOD OF SEARCHLIGHT VENTILATION.

1,318,701.

Specification of Letters Patent.

Patented Oct. 14, 1919.

Application filed April 3, 1916. Serial No. 88,490.

To all whom it may concern:

Be it known that I, ELMER A. SPERRY, a citizen of the United States, residing at 5 borough of Brooklyn, New York city, in the county of Kings and State of New York, have invented Improved Methods of Searchlight Ventilation, of which the following is a specification.

This invention relates especially to searchlights employing flaming arc electrodes operated with heavy currents in which great heat and a large quantity of fumes are produced. The heat produced is so intense as to crack the mirror and damage the drum and other 15 parts of the searchlight mechanism unless an efficient cooling system is employed. Also the white fumes speedily condense on the light concentrating device shown as a mirror, window and elsewhere and in a short time seriously impair the brilliancy of 20 the beam. The main objects of the invention are to dissipate this heat by cooling the drum, mirror, electrode holders, and other parts and to force or draw out the fumes 25 without causing flickering of the arc. The invention concerns especially the type of searchlight disclosed in my co-pending application on improvements in searchlights, Serial No. 21661, filed April 16th, 1915. 30 Other objects of the invention are to improve upon certain details of construction of the lamp shown in said application.

Referring to the drawings, in which what I now consider to be the preferred form of 35 my invention is shown: Figure 1 is a vertical cross section of a searchlight, the section being taken on line 1—1 of Fig. 2.

Fig. 2 is a vertical longitudinal section 40 of the same.

Fig. 3 is a detail of the drum showing one 45 of the air passages.

Fig. 4 is an enlarged sectional view of a portion of the positive electrode holder.

Fig. 4^a is a section on line a—a of Fig. 4. 50 Fig. 4^b is a detail of Fig. 4.

Fig. 5 is a corresponding view of the negative holder.

Fig. 6 is a front view of Fig. 5.

Fig. 7 is a rear view thereof.

55 Fig. 8 is an enlarged sectional view show-

ing the mounting of the negative holder within the control box.

Fig. 9 is a section of a portion of Fig. 5 on line 9—9, Fig. 6.

Fig. 10 is a top view of a portion of Fig. 5. 55

Fig. 11 shows a modification of the means for mounting the light concentrating device.

Fig. 12 is a detail of certain of the parts shown in Fig. 8. 60

As a means for creating a circulation of air through the drum 1, I prefer to employ a positive exhaust fan 2, driven by an electric motor 3 and supported in a box 4 at the top of the drum and preferably above the 65 arc flame 5. The heated air and fumes drawn from the drum pass out the openings 6, 7 as indicated by the arrows. Prior to entry into the drum, the air is caused to cool certain parts. The incoming air, or a 70 portion thereof, is guided over the mirror 8—preferably the back of the mirror—so that the mirror will be cooled uniformly.

The problem of preventing searchlight 75 mirrors from cracking when an arc employing over 100 amperes is employed is much more perplexing than might appear from a superficial inspection of the subject. I have found that merely cooling the mirror by a current of air or otherwise as attempted 80 by prior workers in the art is worse, if anything, than no cooling at all, since unequal cooling of the mirror surface will invariably crack it. By many experiments, involving the exploration of the mirror surface by means of thermal couples, I have determined that by introducing the air adjacent the top of the mirror, which is the 85 part receiving the most heat and causing it to flow downwardly over the mirror a substantially uniform cooling is effected, since the coldest air is brought into contact with the hottest part of the mirror. By my invention the breakage of the mirrors is reduced almost to the vanishing point. 90

The air is introduced adjacent the top of the mirror through an opening 9 in shield 10 and descends as indicated by the arrows to points 11, 12 near the bottom of the mirror, (Fig. 3) where it is led into the drum 100

through baffle plates 13, 14 designed to deflect the air away from the arc to prevent its flaring and flickering. The plates also serve to cause the air to sweep the walls of the drum and to distribute the air currents throughout the length of the drum. The air escapes at 15 between plate 13 and the drum so that it is guided over the inner surface of the drum. An additional baffle plate 16 may 10 be provided if desired.

It will be noted that the air introduced into the drum, or the greater part thereof is warmed somewhat prior to entry into the drum, by passing down over the back of the 15 mirror. By this means, I avoid the contact of cold air with the bottom or cooler portions of the mirror.

On account of the location of motor 3 at the top of the drum, I prefer to employ a 20 ventilating system therefor to prevent overheating. The gases exhausted from the drum are not well suited for this purpose, being both hot and corrosive. Accordingly, I prefer to utilize the outside air for this 25 purpose and to shield the motor from the exhaust gases. I may provide a small fan 100 on the upper end of the motor shaft designed to draw air in through holes 101 and force it through the motor 3 and out openings 102, 103, as shown by arrows 130, or simply the natural convection currents may be utilized, in event the air would circulate in the opposite direction from that shown by the arrows 130.

35 In practice, I have found that the dull, metallic drum becomes very much hotter than the bright mirror, which reflects the heat and light rays, so that by interposing an artificially cooled member 17 between the 40 drum 1 and mirror 8 I am enabled to keep the mirror cool by preventing the heat of the drum from being communicated to the mirror. Member 17 is shown as a hollow ring having openings 18 to the air near the 45 top thereof and being in communication with plates 13, 14 near the bottom, so that the air circulates down the ring as shown by arrows 19. Ring 17 also serves to shield the clips 110 supporting the mirror from the 50 direct radiation from the arc.

The lamp portion of the searchlight comprises a positive electrode holder 20, and a negative electrode holder 21, through each of which the electrodes are fed automatically. On account of the rapid consumption of the positive carbon in this type of lamp, I find it necessary to employ a very long carbon 121, which is allowed to project through an aperture 122 in the window 123. 55 A tubular holder 124 may also be provided, which is secured to the front of the drum by means of rods 125. Both holders are cooled by an air blast or current and both holders serve to introduce current into their

respective electrodes. Holder 20 is supported on a flattened tube 22 through which air is led into the holder. The body of the holder incloses at its rear feeding and rotating mechanism (not shown) and at its forward portion comprises cooling ribs 24, 70 around which is placed a shield 25 having a slot 26 near its top. Radial brushes 70 are employed to introduce the current into the electrode. The brushes are yieldingly pressed against the carbon by springs 71, 72 extending through the holder and secured adjacent each end to equalizing bars 73 extending across the brushes. On account of the intense heat near the arc and for the purpose of preventing a too rapid conduction of 80 heat away from the crater I attach a highly refractory sleeve 27 to the forward portion of the holder. The flaring end 28 of the sleeve is clamped at the forward end, preferably between shield 25 and the end of the holder, 8 air-tight gaskets 127 being interposed therebetween. The ribs 24 are cut away at the bottoms so that the air coming in through tube 22 may circulate through all of the ribs. After passing up over the ribs, the 9 air emerges through slot 26 with considerable velocity. In order to furnish a sufficient supply of air for this purpose, I employ a motor 25 to operate a blower 25' located in the control box 126 and connected 9 to tube 22 through passageway 27. Blower 25' is also connected to the tube 28 supporting the negative holder 21 through said passageway and a telescopic tube 29 (Fig. 8), to allow for the movement of the holder 1 in striking the arc. The tube 28 is supported on a rotatable base 30, which is swiveled on a sliding carriage 31 supported on a guideway 32 in box 126. Base 30 is provided with a central hollow extension 33 adapted to lead air from tube 29 up to tube 28. The carriage 31 is moved on the guideway by means of the striking solenoid 34, a bell crank lever 35 being swiveled adjacent one end to said carriage and at the other end connected to the core 36 of said solenoid.

Member 30 is made rotatable to facilitate the insertion of the negative carbon, when the lamp is within the drum. A catch 37 may be provided to properly position the holder. On account of the small diameter of the negative carbon, and the heavy currents employed, its resistance causes a considerable loss of energy unless the current is introduced as close to the arc as possible and in addition the electrode becomes heated to a white heat causing oxidation and vaporization back of the arc. The negative holder is designed with reference to this condition, by providing means to introduce current very close to the arc.

The negative holder proper comprises a body portion 38 in which air ducts 39 are

provided all of which are in communication with tube 28. Hinged or flexible contact fingers 40 are secured to the forward portion of the body, the fingers being resiliently pressed into engagement with the electrode 41 by means of flat springs 42. Fixed guides 43 are positioned between the fingers, against which pins 44 on the fingers are adapted to bear when the carbon is withdrawn. The feed rollers 128 for the carbon are mounted on pivoted brackets 45, 46 and are held with a yielding pressure against the carbon by means of spring 47 extending between the brackets. The rollers are rotated from feed shaft 48 by means of gears 49, 50, 51 and 51'. In order to release the rollers, when the holder 21 is turned around for insertion or release of a carbon, I may provide a rod 52 which engages a cam surface 53 on carriage 31 on rotation of the member 30 and is lifted thereby. Links 54 are connected at the top of the rod to brackets 45, 46, so that when the rod is lifted the brackets will be spread and the rollers released from the electrode. The carbon may then be removed or replaced through a slide or door 126' in the side of drum 1.

The air ducts 39 lead out under springs 42 and direct the air along the contact fingers 40. The size of the ducts is regulated to limit the amount of air escaping so as to prevent the arc from causing flickering of the air. The amount of air passed through the negative holder is small as compared to the amount passed through the positive holder.

There are at least two reasons for employing a comparatively rapid circulation of air to cool the positive holder. One is that the positive electrode tip is heated to such a high temperature, that it is necessary to intensively cool the holder between the arc and the point where the current is led into the carbon through brushes 70, if the brushes are placed close to the arc. Another reason is that the heated air in escaping from slot 26 with considerable velocity entrains the fumes and vapors from the arc and carries them directly to the exhaust fan 2, so that they are not allowed to fill the drum or come in contact with the mirror.

The two motors 3 and 25 are preferably connected in parallel on the main circuit, and are provided with separate starting switches 55 108, 105 and regulating rheostats 108', 107, an independent switch 104 and rheostat 106 being provided for the arc, so that the various parts may be operated independently.

Fig. 11 shows a slightly modified form of mirror mounting in which the mirror 8 is supported from the drum by means of clips 8', which are preferably formed of resilient metal. Heat insulating material 8" is interposed between the clips and the glass.

An artificially cooled ring 17', similar to ring 17 is also provided, which is designed so as to shield the clip 8' from the direct radiation from the arc. Ring 17' also aids in supporting the clips so that they need not be in contact with the hot drum over a large surface, but are secured only to the cooled ring. By shielding the clips from the intense arc rays, in addition, I am enabled to maintain the mirror support at about the same temperature as the mirror.

When the operating current is switched on the arc will be struck by the rapid retraction of the entire negative holder 21 as described, and at the same time the feeding mechanism for feeding the electrodes through the holders placed in operation. At the same time the ventilating and cooling means will be placed in full operation since said means are power driven and do not depend entirely upon convection currents for their operation. The blower 25' will force air up through the hollow legs of the electrodes and out of the top of the positive electrode. This stream of air emerging to one side and directed toward the exhaust fan 3 entrains all of the fumes of the arc and carries them directly to the exhaust fan before they come in contact with the mirror or drum. At the same time, the air drawn in through the baffle plates 16 around the drum create other currents of air directed toward the exhaust fan (see Fig. 1), but not in contact with the arc. The entire drum is thus perfectly ventilated and at the same time direct drafts on the arc are avoided. By having the ventilating and cooling means positively driven and directed I also secure the advantage that the ventilating system will operate in any position of the searchlight. This is of great advantage when the searchlight is used for picking up air craft since in such a case it is often desirable to place it in a substantially vertical position.

In accordance with the provisions of the patent statutes, I have herein described the principle of operation of my invention, together with the apparatus, which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having described my invention, what I claim and desire to secure by Letters Patent is:

1. In a searchlight, the combination with the light concentrating device and drum, of

- a fan connected therewith for causing a circulation of air through the drum and means for deflecting the incoming air away from the arc and around the walls of the drum.
5. 2. In a searchlight, the combination with the light concentrating device and drum, of a fan connected therewith for causing a circulation of air through the drum, an inlet passage adapted to guide the air over the 10 light concentrating device, and means for deflecting the incoming air around the interior walls of the drum to ventilate the interior of the searchlight.
15. 3. In a searchlight, the combination with the light concentrating device and drum, of a fan connected therewith for causing a circulation of air through the drum, an inlet passage adapted to guide the air downwardly over the light concentrating device, 20 and means for deflecting the incoming air around the interior walls of the drum to ventilate the interior of the searchlight.
25. 4. In a searchlight, the combination with the light concentrating device and drum, of a fan connected therewith for causing a circulation of air through the drum, an inlet passage adapted to guide the air over the light concentrating device, means for deflecting the incoming air around the walls of the 30 drum, and means for introducing a current of air adjacent the electrode holders.
35. 5. In a searchlight, the combination with the light concentrating device and drum, of a fan connected therewith for causing a circulation of air through the drum, an inlet passage adapted to guide the air over the back of the light concentrating device, means for deflecting the incoming air around the walls of the drum, and means for introducing 40 a current of air toward the said fan adjacent the electrode holders.
45. 6. In a flaming arc searchlight, the combination with the light concentrating device and drum, of a fan connected therewith for causing a circulation of air through the drum, an inlet passage adapted to guide the air over the back of the light concentrating device, means for deflecting the incoming air around the walls of the drum, and an air 50 inlet adjacent an electrode holder.
55. 7. The method of cooling searchlight drums which consists in introducing air within, around and adjacent the inner walls of the drum and also adjacent the central region of the drum.
60. 8. In combination, a searchlight drum, baffle plates within, adjacent and approximately concentric to the periphery of said drum, said drum being provided with an opening permitting entry of air thereto and means for creating a draft in the space between said baffle plates and drum.
65. 9. The method of cooling searchlight drums which consists in introducing air within and adjacent the inner walls of the drum, in directing it circumferentially around the drum and in introducing a separate supply of air adjacent the central portion of the drum.
70. 10. The method of cooling searchlight drums which consists in introducing air within and adjacent the inner walls of the drum, in directing it circumferentially around the drum, in distributing it longitudinally of the drum and in introducing a 75 separate supply of air adjacent the central portion of the drum.
75. 11. A ventilating means for electric arc searchlights, comprising an exhaust or suction device adapted to exhaust the air from the drum and air blowing means for introducing air into the drum in a direction at a substantial angle to one of the electrodes.
80. 12. A ventilating means for high intensity electric arc searchlights, comprising means 85 for exhausting air from the drum and an air blowing means for introducing air into the drum adjacent to, but not in contact with the arc.
85. 13. A ventilating means for electric arc searchlights, comprising the combination with a drum, an exhaust fan adapted to draw air from said drum and means for introducing a draft of air adjacent to but 90 directed away from the arc.
90. 14. In a searchlight, a drum, a pair of arc electrodes mounted within said drum, means for drawing air from said drum and means for blowing air into said drum adjacent to the arc, and in a direction at a substantial 95 angle to the electrodes.
95. 15. In a searchlight, a drum, a pair of arc electrodes within said drum, means for exhausting air from said drum and means for blowing air into said drum toward said first named means and away from the arc.
100. 16. In a searchlight, a drum, a pair of arc electrodes, means for exhausting air from said drum, means for blowing air into said drum and a passage for introducing the air from the last named means into said drum at a substantial angle to a line connecting the tips of the electrodes.
105. 17. In a searchlight, a casing, an electrode holder within said casing, means for exhausting air from said casing and means for introducing an air blast at a point within said casing on the side of said electrode holder toward said first named means.
110. 18. In a searchlight, a casing, an electrode holder mounted within said casing, means for exhausting air from said casing and means for blowing air through said holder, said holder being provided with an opening on the side thereof which is toward said air 115 exhausting means.
120. 19. In a searchlight, a drum, an exhaust opening therein, means for drawing air 125

through said opening, means for producing an arc within said drum, and means for causing and introducing a blast of air into said drum at a place spaced from said opening but located a shorter distance from said opening than the arc.

20. An electrode holder comprising a body portion provided with a central aperture for the electrode, and with cooling ducts, and axially extending spring pressed fingers attached to said body, said ducts being adapted to cause a circulation of air along said fingers to cool the same.

21. In a searchlight, means for producing an arc including an electrode holder, axially extending contact fingers on said holder for introducing current to the electrode close to the arc, ducts on said holder adapted to direct air along said fingers and means for causing air to pass through said ducts.

22. In a searchlight, an electrode holder, axial fingers connected to said holder adapted to introduce current close to the active end of the electrode, and means comprising air ducts on said holder for directing a cooling draft along said fingers.

23. In a searchlight, means including an electrode holder for producing an arc, axial fingers connected to said holder adapted to introduce current to the arc and means comprising air ducts on said holder for directing a cooling draft along said fingers.

24. In a searchlight, an electrode holder located adjacent the arc, means for feeding the electrode through the holder, a standard for supporting the electrode from adjacent the bottom of the drum, a slidably mounted base for the standard, and means for sliding the base to strike the arc.

40 25. In a searchlight, an electrode holder located adjacent the arc, means for feeding the electrode through the holder, a standard for supporting the electrode from adjacent the bottom of the drum, and means for moving the holder and standard toward and away from the arc for striking the arc.

26. The combination with a searchlight drum, of an electrode holder located within the drum, a swivel mounting for the holder whereby the electrode may be turned toward the walls of the drum and a door in the drum substantially opposite the electrode when so turned, whereby the electrode may be removed from outside of the drum without removing the holder.

27. The combination with a searchlight drum, of an electrode holder located within the drum, feed rollers yieldingly mounted on the holder, a swivel mounting for the holder, means operated by turning of the holder for spreading said rollers, and a door in the drum opposite said holder, whereby the electrode may be renewed from without the drum.

28. In combination, a searchlight drum, 65 an electrode holder located within the drum, feed rollers yieldingly mounted on the holder, a swivel mounting for the holder and means operated by turning of the holder for spreading said rollers.

70 29. In combination, a searchlight drum, an electrode support located within the drum, means for gripping an electrode on said support, a swivel mounting for the support and means operated by turning the support for releasing said gripping means.

30. In combination, a searchlight drum, an electrode support located within the drum, means for gripping an electrode on said support, a swivel mounting for the support and means operated by turning the support for spreading said gripping means.

31. A ventilating means for electric arc searchlights comprising, in combination with the drum, an exhaust fan adapted to 85 draw air from said drum and means for introducing a draft of air directed away from the arc and toward said fan.

32. The combination with a searchlight, having a reflector, of a back plate spaced 90 from said reflector, an opening to the air adjacent the top of the reflector and means for drawing air in through said opening and downwardly over the back of said reflector to cool the same uniformly.

95 33. The combination with a searchlight, having a reflector and a drum, of a back plate spaced from said reflector, an opening to the air adjacent the top of the reflector, a passage leading from adjacent the bottom of 100 the reflector, into the interior of the drum and means for drawing air in through said opening downwardly over the back of said reflector and into said drum.

34. In a searchlight, the combination with 105 the reflector and drum, of a fan connected therewith for causing a circulation of air through the drum, and an inlet passageway adapted to guide the air downwardly over the reflector, and into the drum.

110 35. In a searchlight, the combination with a reflector and drum, of a fan connected therewith for causing a circulation of air through the drum, and an inlet passageway adapted to guide the air over the back of 115 the reflector and into the drum.

36. In a searchlight, the combination with a drum and a reflector, of a member having a passage therethrough for supporting the device from the drum and means for circulating a cooling medium therethrough.

120 37. In a searchlight, the combination with a drum and a reflector, of a member having a passage therethrough for supporting the projector from the drum, a baffle plate arranged in rear of the reflector forming a second passage and means for causing a circulation of air through both passages.

38. In a searchlight, a metallic drum, a vitreous reflector, and an artificially cooled means for supporting the projector from the drum.
- 5 39. In a searchlight, the combination with a reflector, a drum and a source of light, a clip for supporting the mirror from the drum and a shield for the clip located between it and the said light source.
- 10 40. In a searchlight, the combination with a reflector, a drum and a source of light, a clip for supporting the mirror from the drum, a shield for the clip located between it and the said light source and a positive 15 means for cooling said shield.
41. In a searchlight, the combination with
- a reflector, a drum and a source of light, a clip for supporting the mirror from the drum, an artificially cooled shield for the clip located between it and the said light 2 source, said clip being supported from the drum by means of said shield.
42. In a searchlight, the combination with a drum, a hollow electrode holder positioned therein, a duct leading from without the 2 drum to within said holder, a blower for forcing a current of air into said duct and holder, and an exhaust fan for exhausting the heated air so produced.

In testimony whereof I have affixed my 3
signature.

ELMER A. SPERRY.
